BOTTLE CARRIER

Charles H. Kruea, Fort Thomas, Ky., assignor, by direct and mesne assignments, of one-sixth to Robert L. Black, one-sixth to E. Webster Harrison, and one-sixth to Robert B. Harrison, all of Cincinnati, Ohio

Application September 1, 1938, Serial No. 227,999

2 Claims. (Cl. 224—45)

The present invention relates to a bottle holder and has for an object the provision of a simple, one-piece holder or support means in which a bottle is normally suspended vertically from the bulbous part of the bottle neck and is positively held against accidental separation therefrom.

A further object of the invention is to provide a device of this character which requires manual tilting of the bottle to an angle of the order of 70° or more from its normal upright position in order to enter the bottle into or remove the bottle from the holder when the latter is in a substantially horizontal position.

Another object of the invention is to provide a holder of the class described that is adapted to be inexpensively formed of rigid sheet material and which may be arranged in a wide variety of forms for use as a fixed support or as a portable carrier.

A still further object of the invention is to provide a multiple bottle carrier that occupies a minimum of space and which permits safe transportation of bottles regardless of whether said carrier is partially or fully loaded with bottles.

These and other objects are attained by the means described herein and disclosed in the accompanying drawing, in which:

Fig. 1 is a perspective view of a simple form of multiple bottle carrier embodying the invention.

Fig. 2 is an end view showing a slightly modified form of carrier of the invention in an unbalanced condition, the bottle being largely broken away.

Fig. 3 is a fragmental side elevational view showing the bottle holder of Fig. 2 with a bottle therein, and showing in dotted lines the angular position of the bottle for entering or removing the latter from the holder.

Fig. 4 is a plan view showing a development of the holder of Fig. 3.

Fig. 5 is a fragmental side elevational view of another modified form of the holder of the invention with a bottle seated therein and showing in dotted lines the position required for entering and removal of the bottle.

Fig. 6 is a plan view of a development of the holder of Fig. 5.

Fig. 7 is a fragmental perspective view of a holder of the invention adapted for wall mounting.

Fig. 8 is a side elevational view of a single carrier of wire or strip metal for a bottle or jug in operative engagement about the neck of such a container.

Fig. 9 is a front elevational view of the device of Fig. 8 with the container removed.

It is known in the art to provide bottle holders wherein the bottle is suspended from the neck, but the prior art devices have been open

to the disadvantage of requiring some auxiliary means to retain the bottle against accidental separation during movement of the holder.

In the device of the present invention the requirement for auxiliary means is eliminated and a less expensive and more effective device results therefrom.

Referring now to the drawing, Fig. 1 shows a carrier adapted to hold a plurality of beverage bottles of the types used for soft drinks, carbonated water, beer, and other popular beverages. The bottles mentioned have a common characteristic in that a bulbous portion 10 is provided closely adjacent the mouth. Immediately below the bulbous portion these bottles all have a restriction 11 of an exterior diameter of approximately one inch. Below restriction 11 the bottle necks assume various tapered shapes.

In providing for the reception and positive retention of this large class of beverage bottles, the present invention preferably employs a sheet metal body 12 which is cut inwardly from the edge thereof to form a way 13 having parallel bounding edges 14 which are joined by a semi-circular edge 15 having a radius large enough to receive the restricted neck portion 11 with very slight clearance. The parallel bounding edges 14 will thus pass the restricted portion 11 of the bottle between them but no appreciable part of the bulbous enlargement 10 above the restriction 11 can be passed between these parallel edges. The essence of the present invention resides in providing the semi-circular arcuate edge 15, or its equivalent, to embrace substantially one-half of the restriction 11 of a bottle and to continue the parallel edges 14 outwardly for a distance less than the radius of the restriction 11 beyond the center of the bottle neck and to then turn said parallel edges upwardly or outwardly and inwardly so as to provide one or more points along said edges 14 to contact the bulbous portion 10. Since these upwardly turned portions are parallel and are spaced apart at a lesser distance than the major diameter of the bulbous portion 10, a bottle neck can be entered only by tilting the bottle or the body 12 to such an angle as to enable the extreme ends of prongs 16 to be passed transversely across the restricted portion 11 and beyond a plane of the axis of the bottle. The ends of prongs 16 will then find a place, between said plane of the axis of the bottle and a parallel plane tangent to the bulbous portion 10, where said points may pass upwardly to embrace the portion 10. Assuming the body 12 to be in a horizontal position, the bottle is suspended by the bulbous portion thereof resting over the arcuate edge 15 and on some point on the parallel edges 14. The bottle cannot be moved outwardly nor upwardly nor inwardly because of binding on opposed portions of the par-

allel curved edges 14 on the bulbous portion beyond the plane of the axis of the bottle. Removal is therefore accomplished only by the relative tilting of the bottle and the body 12 away from each other which allows the ends of prongs 16 to ride downwardly over the bulbous portion while the arcuate edge 15 rides upwardly thereover. When the tilting has progressed to such extent that both the ends of prongs 16 lie in the plane of the restriction 11, the bulbous portion 10 is entirely free of binding upon any part of the holder. The bottle may then be lifted away from the holder. Since this angle of tilting is required to be of the order of 70° or more from a perpendicular to the body 12, it is impossible to accidentally dislodge a bottle completely from the holder. The suspended bottle can not shift horizontally in any direction and can be tilted in only one direction, hence such bottles cannot strike adjacent bottles or any other adjacent object. In the form shown in Fig. 1 the metal is turned upwardly at right angles so that the upturned parallel edges will have a single pair of contact points on the bulbous portion 10 of a bottle. The points of contact shift as the carrier is progressively tilted.

In the form shown in Fig. 5 additional metal is provided on the ends of prongs 16 and this metal is turned back inwardly when the prongs are turned up as in the device of Fig. 1. In the forms shown in Figs. 2 and 3, the tongues 16 of the metal bounding the way 13 are turned arcuately upwardly and inwardly (see Fig. 3). Slightly beyond the radial center of the curved edge wall 15, beginning at points lying in the dotted line 17 as shown in the developed form of Fig. 4, the parallel edges 14 curve upwardly and inwardly to terminate at a point which will lie above the plane of the largest diameter of bulbous portion 10 and outwardly beyond the axis of said bulbous portion and bottle neck. The curved parallel edges 14 of the curved arms 16 are too close together to permit the bulbous portion 10 of the bottle neck to be entered between them. When the axis of the bottle is turned up to a suitable angle the bulbous portion of the bottle may rest partially at least against the arcuate wall 15 and the curved tongues 16 terminate on the opposite side of the bulbous portion 10 as shown in dotted lines in Fig. 3.

For single or multiple holders adapted for wall mounting the sheet metal of the device has suitable flanges 19 formed thereon for strength and one or more screw receiving lugs 20 to enable ready mounting on a wall surface 21.

In providing a carrier for a single bottle or jug stiff wire stock or strip metal is preferred. The strip or wire is bent intermediate its ends to form an arcuate seat portion 22 and the ends continued from said bent portion as a pair of short parallel edges 23 and then turned upwardly as parallel edges 24. The seat and parallel edges thus formed correspond in form substantially to the bottle neck supporting portions of the device of Fig. 1. The remaining free ends of the wire are formed into a bail 25 which may be bent to suitable shape and may be provided with a tubular handle member 26.

The multiple bottle carriers as exemplified in Figs. 1 and 2 have a plurality of bottle receiving ways 13 disposed in a more or less compact rela-

tion as desired. Bails 27 connected to a suitable handle 28 provide an arrangement that can be folded flatly upon body 12 at any time. This enables the use of this type of carrier by distributor, dealer and consumer. The bottles remain securely seated in the carrier regardless of whether the latter is uniformly or non-uniformly filled with bottles. When such carrier having one or more bottles is placed on a table surface the bottles rest on their own bottoms and the carrier is supported by the bottles without danger of releasing any of the bottles when the carrier is again picked up. When suspended by its handle the carrier assumes a horizontal position or an inclined position depending on the number and disposition of the bottles therein. The angle at which the bottles must be tilted before lifting them from the suspending seats is such as to render it impossible to accidentally release a bottle without the prescribed degree of tilting and lifting. In all of the embodiments illustrated and in contemplated modifications thereof within the scope of the invention the essential features are the provision of normally horizontal parallel edges, shorter than a radius of restriction 11 of the bottle neck with a connecting edge in a plane therewith to contact the restriction 11 below the enlargement 10 and position the ends of the parallel edges on opposite ends of a diameter of the bottle neck and upturned parallel edges forming a continuation of the said horizontal edges to contact the circumference of the enlargement 10. Such an arrangement will accommodate bottles having enlargements 10 of various different contours.

What is claimed is:

1. A device for carrying a bottle having a bulbous portion comprising, a support member providing a slot of sufficient width to admit the neck portion of the bottle below the bulbous portion, upturned portions extending upwardly from either side of said slot and engaging the bulbous portion forwardly of the center of the bottle and inwardly of the width of the bulbous portion when the back portion of the neck of the bottle engages the inner end of said slot, said slot being of a depth in relation to the upturned portions for causing a wedging action to occur on the bottle between the inner end of the slot and the upturned portions engaging the bulbous portion of the bottle when the body of the bottle tends to swing inwardly of the slot.

2. A multiple carrier for beverage bottles comprising a rigid sheet metal body having bottle neck receiving slots in the edges thereof, each slot being of sufficient width to admit the neck portion of the bottle below the bulbous portion, upturned portions extending upwardly from either side of the particular slot and engaging the bulbous portion forwardly of the center of the bottle and inwardly of the width of the bulbous portion when the back portion of the neck of the bottle engages the inner end of said slot, said slot being of a depth in relation to the upturned portions for causing a wedging action to occur on the bottle between the inner end of the slot and the upturned portions engaging the bulbous portion of the bottle when the body of the bottle tends to swing inwardly of the slot.
